[57] CLAIM

The ornamental design for a pyramid clip, shown and described.

DESCRIPTION

FIG. 1 is a front perspective view of a pyramid clip showing my new design;

FIG. 2 is a front elevational view thereof;

FIG. 3 is a bottom plan view thereof;

FIG. 4 is a top plan view thereof; and,

FIG. 5 is a right side elevational view, the left side being a mirror image thereof.

The appearance of the rear of the clip forms on part of the claimed design.

The fragmentary showing of the clipboard in FIG. 1 and the structure in FIGS. 3 and 5, all depicted by means of broken lines, have been shown for illustrative purposes only and form no part of the claimed design.
